(57) **CLAIM**

I claim the ornamental design for a headphone, as shown and described.

DESCRIPTION

This patent or application file contains at least one drawing executed in color. Copies of this patent or patent application

with color drawing(s) will be provided by the Office by request and payment of the necessary fee.

FIG. 1 is a perspective view of a first embodiment of a headphone, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a color, perspective view of a second embodiment of a headphone, the color drawing is necessary to clearly show in the presence of colors within the design;

FIG. 9 is a color, front elevational view thereof, the color drawing is necessary to clearly show the presence of colors within the design;

FIG. 10 is a color, rear elevational view thereof, the color drawing is necessary to clearly show the presence of colors within the design;

FIG. 11 is a color, right side elevational view thereof, the color drawing is necessary to clearly show the presence of colors within the design;

FIG. 12 is a color, left side elevational view thereof, the color drawing is necessary to clearly show the presence of colors within the design;

FIG. 13 is a color, top plan view thereof, the color drawing is necessary to clearly show the presence of colors within the design; and

FIG. 14 is a color, bottom plan view thereof, the color drawing is necessary to clearly show the presence of colors within the design.

FIG. 15 is a perspective view of a third embodiment of a headphone;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof; and,

FIG. 21 is a bottom plan view thereof.

Broken lines are for illustrating portions of the headphone which form no part of the claimed design.

(Continued)

The stippling illustrated in the third embodiment represents a contrast in appearance as shown.
